UNITED STATES PATENT OFFICE.

HIRAM F. McNUTT AND CHARLES E. BALLINGER, OF RICHMOND, INDIANA.

CRACKER-CUTTER.

1,102,676.

Specification of Letters Patent.

Patented July 7, 1914.

Application filed February 17, 1913. Serial No. 748,835.

To all whom it may concern:

Be it known that we, HIRAM F. McNUTT and CHARLES E. BALLINGER, both citizens of the United States, residing in the city of 5 Richmond, in the county of Wayne and State of Indiana, have invented certain new and useful Improvements in Cracker-Cutters, of which the following is a full, clear, and comprehensive specification and exposi- 10 tion, being such as will enable others to make and use the same with exactitude.

Our invention relates to certain specific improvements in cutter-heads for cracker machines, the machine itself being a non- 15 essential to a full understanding of this invention, therefore only such parts of the machine are shown which are necessary to a full explanation of the operation of the cutter-heads and of the improvements which 20 are shown herein.

The specific improvements which we have invented will be brought out in the course of the following description, the preferred manner for their construction and arrange- 25 ment being shown in the accompanying two sheets of drawings, in which—

Figure 1 shows an underside or face view of the face-plate, together with certain of the devices which operate therethrough or 30 are connected therewith. Fig. 2 is a top plan view of the die-plate, showing our means for connecting certain of the devices thereto. Fig. 3 is an end elevation of the cutter head, also showing an edge view of 35 the carrier-belt, a portion of the table, and the cross-arm of the machine in section. Fig. 4 is a vertical section taken centrally through one of the twelve cutter mechanisms, for instance on line 4—4 of Fig. 1. Fig. 5 is a vertical central section taken 40 through one of the twelve cutter mechanisms, at right-angles to that of Fig. 4, for instance on line 5—5 of Fig. 1. Fig. 6 is a perspective view of the upper portion of 45 one of the twelve peripheral cutters or devices. Fig. 7 is a perspective view of one of the twelve milling-dies or devices. Fig. 8 is a perspective view showing various 50 devices and parts of one of the twelve cutter mechanisms, including the clearing plunger, initial die, and dotters. And Fig. 9 is an 55 isometrical detail view of one member of the twelve pairs of clearers.

Similar indices denote like parts through- 55 out the several views.

In order that our invention and its advantages may be more fully understood we will now take up a detailed description thereof, in which we will set forth the construction as clearly and as comprehensively 60 as we may.

In order that the description may be simplified we will refer to the mechanism, with which our invention is to be used, as the machine, only a few parts of which are shown 65 herein; we will refer to all of the parts, collectively, which are located between the stops G, which form stationary parts of the machine, and the cross-arm D, which is a movable part of the machine, as the cutter-head; 70 to each of the twelve groups of parts, shown in Fig. 1, as the devices; and to each member of the several devices as the peripheral-cutter, the clearers, the milling-die, the initial-die, the cutters and the plunger or 75 clearer-head.

The cutter head includes the face-plate A, same having a plurality of apertures a formed therethrough, as shown in Fig. 1. Extending out from near each corner of 80 plate A are the ears a'. And projecting out from each end of said plate A, beyond said ears, are the tongues A'.

Letter B denotes the body-plate of the cutter-head, same being of substantially the 85 same size as the face-plate, with the exception of the tongues A'. The under face of the body-plate is located parallel with the face-plate. The sides of the plate B are formed with upwardly extending flanges 90 and enlarged corner portions, in order to add strength thereto. Extending across each end of the plate B, and secured to the corner portions thereof, are the yokes C, same being detachably secured by the screws 95 b, as shown in Fig. 3.

Letter D denotes the cross-arm of the machine, same being detachably secured to the two yokes by the bolts d. Said cross-arm extends beyond the yokes at each end and 100 the projecting portions thereof are slidably mounted in vertical guide-way of the machine whereby it may be moved up and down carrying the entire cutter-head up and down therewith. By the above it is apparent that the cutter-head is suspended over the surface of the table E, over which latter travels the carrier-belt F, the latter 105 operating in a direction at right-angles to the length of the plate A.

Extending up from each edge of the table E is a flange each carrying one of the stops G against which the tongues A' are adapted to impinge as the cutter-head is moved downward, thereby preventing the face of the plate A from contacting with the carrier F.

Seated in suitable cavities in the upper face s of the ears a' are the four helical springs I, the upper ends of said springs being seated in cavities formed in the under face of the plate B.

Numerical 1 denotes the die-plate, same being slightly less in length than that of the plate A, and of only about one-half the width thereof, and it is located centrally of and above the body-plate B, as shown in Fig. 3. An aperture is formed through the die-plate 1 near each corner thereof, in which are disposed the threaded and reduced upper ends of the standards 2, the shoulders of said standards contacting with the under face of the die-plate. The lower ends of said standards 2 are rigidly secured to the face-plate A, there being corresponding apertures formed through the body-plate B through which said standards are freely disposed. The said plate 1 is removably secured to the upper ends of said standards by the nuts 3, as shown.

Rigidly secured in the center and near each end of plate 1, and extending downward therefrom, are the two stops 4, their lower ends being adapted to impinge the upper face of the plate B, as in Fig. 3, thereby limiting the downward movement of plate A beyond a certain distance with relation to the plate B, the springs I normally retaining said plates A and B apart, as shown in Fig. 3.

We will now describe the cutter devices, and as they are all identical with each other a description of one will answer for all. Each of said devices is made up of a plurality of parts,—wherein numeral 5 denotes the peripheral cutter, that is the main cutter which cuts out the form of the cracker, same being tubular and adapted to fit inside its aperture a of the plate A, the lower or cutting edge of cutter 5 being formed to cut the dough of proper size for a cracker. Extending out opposite to each other, slightly below the upper end of the cutter 5, are the ears 5' and 5''. The upper end of the cutter 5 is adapted to contact with the under face of the plate B, to which it is rigidly secured as hereinafter set forth. Located around inside the cutter 5 are the two segmental clearers 6 and 7, the two extending almost entirely around and adjoining the inner periphery of the cutter 5. When the cutter-head is raised then the lower edges of the clearers will be substantially even with the lower edge of the cutter 5. Extending up from the center of each of

the clearers 6 and 7 and formed integral therewith are flat stems, 8 and 9 respectively, each having a reduced tongue portion, 10 and 11 respectively, on its upper end, thereby forming shoulders z and z, shown only in Fig. 9. Said stems 8 and 9 operate loosely in slots which are formed therefor through the plate B, the shoulders z engaging the under face of plate 1, and the tongues 10 and 11 fit in and extend through slots e formed therefor through the plate 1, there also being a horizontal aperture formed through each tongue 10 and 11 for the key or cotter-pin H which is adapted to lie flat on the upper face of the plate 1.

Numerical 12 denotes the milling-die, which is in the nature of a ring or tube, fitting around inside the clearers 6 and 7. Said die 12 has a lower impression-face which is usually staggered or crimped. Extending out opposite to each other from the upper edge of the die 12 are the two ears 12' and 12'' through each of which is a screw-aperture 12^a and 12^b, respectively. Extending down from the upper edge of the die 12, more than one-half the length thereof and midway between the ears 12' and 12'', are the relatively large notches 12^c and 12^d, to provide room for the arms 17 and 18, hereinafter referred to.

Numerical 13 denotes a guide-plate, through the outer portions of which are formed the two screw-apertures 13^a and 13^b, which are same distance apart as are the apertures 5^a and 5^b, and also the same distance apart as are apertures 12^a and 12^b.

Secured to the center of plate 13, by the screw 14, and extending down at right angles to said plate 13, is the initial-die 15.

Rigidly secured to the plate 13 are the four dotters or punches J, K, L and M, same being located near the four corners of the die 15, extending downward parallel therewith, and projecting a short distance therebelow, as shown in Fig. 8.

Formed through the plate 13, on each side and central of the screw 14, and extending parallel with the length of the plate 13, are the two slots 13' and 13''.

Numerical 16 denotes the plunger or clearer-head which fits inside of the milling-die 12, as shown in Fig. 1. Extending up from opposite sides of the plunger 16 are the two arms 17 and 18, which are adapted to operate loosely in the slots 13' and 13'', respectively, and they also extend up through suitable apertures therefor in the plate B. The upper end portions of said arms are reduced to form the respective tongues 19 and 20, thereby forming shoulders y, as shown only in Fig. 8. Said tongues 19 and 20 extend through apertures f formed therefor through the plate 1, with the shoulders y engaging the under-face of said plate 1.

Apertures are formed horizontally through the tongues 19 and 20 to receive therethrough the key H, as shown in Fig. 4.

A square aperture x is formed vertically 5 through the center of the plunger 16, in which may operate the lower portion of the die 15. Also four round apertures s are formed through the plunger 16 through which operate the four dotters J, K, L 10 and M.

Letters N and P denote the two main retaining screws, same being adapted to pass through the apertures 13^a—13^b; 12^a; 12^b; and 5^a—5^b, whereby the plate 13, the die 12, 15 and the cutter 5, are all removably securable to the plate B, as shown in Fig. 5.

From the above it is apparent that the cutter 5; the milling die 12; the letter-die 15; and the dotters J, K, L and M, are all suspended from and are carried by the body-plate B. Also that clearers 6 and 7, and the plunger 16, are suspended from and are carried by the die-plate 1.

Heretofore it has been customary to form the clearers 6 and 7, and their stems 8 and 9, of wire, which frequently became bent and out of position and frequently damaged the edge of the cutter 5, or the edge of the milling-die 12. Also it has been customary to 25 thread the tongues 10 and 11 and 19 and 20, securing each in place by a nut, which nuts frequently worked loose, necessitating a great amount of time to remove and replace the parts thereto attached, while in our construction all of the parts of each device, 30 which are connected to the plate 1, are secured by the single cotter-pin H, thereby making the parts more secure, facilitating their removal and replacement, when required for repairs, and reducing the expense 35 connected with the repairs, each of the several parts of each device being thus adapted to be removed and replaced with the removal of other parts of the device. Also 40 heretofore it has been customary to connect the cutter 5, the milling-die 12, and the plate 13, to the plate B each by independent means, whereas in this instance they are all connected thereto by the two screws N and 45 P, thereby simplifying the construction and facilitating their removal and replacement, 50 making the construction more compact and making the parts more secure.

In practice the members 6 and 7 of each 55 pair of clearers may be made integral with each other whereby they will form a single ring or band in place of the two segmental portions as shown.

It will be apparent that when the cutter- 60 head is lifted up that the lower edges or faces of the cutter 5, the clearers 6 and 7, and the plunger 16 will all be practically flush with each other and they will be practically even with the under face of the plate 65 A. Also the edges of the milling-die 12

and the dotters J, K, L and M will be only a slight distance inward (upward) therefrom, that is above the lower face of the plate A. Now as the cross-arm D descends toward the ribbon of dough which may be 70 on the conveyer F, the projections A' of the plate A will strike the stops G thereby preventing further downward movement thereof, and also of the clearers 6 and 7, and the plunger 16, but allowing the cutter 5 75 to continue to move downward, against the resiliency of the springs I, until it contacts with the conveyer F, thereby cutting out the form of the cracker from the dough to be carried by the conveyer. At the same time 80 the dies 12 and 15, and the dotters, will be impressed into the dough of the cracker. After the above the cutter-head will be moved upward, and as the plate A is released from the stops G it will again move 85 away from the body-plate B, thereby causing the cutter 5, the dies 12 and 15, and the dotters, to be drawn in, or up with relation to the plate A, thereby causing the clearers 6 and 7 and the plunger 16 to push 90 the cracker off from device and causing it to remain upon the conveyer.

It should be understood that various styles and shapes of cutters may be employed depending upon the kind of cracker to be made, each cutter-head being arranged for making a particular shape or size cracker, a plurality of cutter-heads being adapted for each machine, each being adapted to be interchangeably secured to the cross-arm D, 95 substantially as shown. Therefore this invention is not limited to the particular size or shape of the devices shown.

Having now fully shown and described our invention, what we claim, and desire 105 to secure by Letters Patent of the United States, is—

1. In a cracker cutting machine, a face-plate having an aperture formed therethrough, a body-plate located above and spaced from the said face-plate, a die-plate located above and spaced from the body-plate and having two pairs of slots there- 110 through which are parallel with each other, a cutter fitting said aperture in the face-plate and extending up and secured to the body-plate, clearers fitting inside the cutter, stems extending upward from the clearers and contacting with the die-plate, 115 tongues projecting up from the stems through and beyond the slots in the die-plate, a plunger located inside the curvature of the clearers, arms extending up from the plunger through the body-plate to the die-plate, tongues extending up from the arms through and beyond their slots in the die-plate, and a single pin passing through 120 corresponding apertures in the tongues and resting flat on the surface of the die-plate, 125 all substantially as set forth.

2. In a cracker cutting machine, a face-plate having an aperture therethrough, a body-plate located above and spaced from the face-plate, a die-plate located above and spaced from the body-plate and having two sets of slots therethrough, a cutter fitting the said aperture in the face-plate and extending upward and secured to the body-plate, a pair of clearers fitting inside the cutter, a stem extending upward from each clearer and normally contacting with the under-face of the die-plate, tongues extending up from said stems through and beyond their respective slots in the die-plate, a plunger located inside the clearer, a pair of arms extending up from the plunger through the body-plate to the die-plate, tongues extending up from said arms through and extend-

ing beyond their respective slots in the die-plate, and a cotter-pin passing horizontally 20 and removably through corresponding apertures formed through all of the said tongues which project above the die-plate with the said cotter-pin resting flat on the top of the die-plate and adapted to retain the clearers 25 and the plunger in operative position, all substantially as set forth.

In testimony whereof we have hereunto subscribed our names to this specification in the presence of two subscribing witnesses. 30
